(57) **CLAIM**

The ornamental design for a handle conversion device, as shown and described.

DESCRIPTION

FIG. 1 is a front elevational view of the handle conversion device showing a new and ornamental design thereof; FIG. 2 is a rear elevational view thereof; FIG. 3 is a right side elevational view thereof; FIG. 4 is a left side elevational view thereof; FIG. 5 is a top plan view thereof; FIG. 6 is a bottom plan view thereof; FIG. 7 is a reduced perspective view thereof; and, FIG. 8 is a perspective view of the handle conversion device shown in FIGS. 1–7 attached to a preexisting handle, shown in dotted lines, that is not a part of the invention, but is merely shown for environment.
